SPRINKLER

William A. Buckner, Fresno, Calif., assignor to
 Buckner Manufacturing Company, Fresno,
 Calif., a copartnership consisting of William
 A. Buckner and Harry Cleason

Application December 29, 1941, Serial No. 424,691

15 Claims. (Cl. 299—69)

This invention relates to water distributing or sprinkling devices, and is more particularly related to that type of sprinkler known as the part-circle sprinkler, wherein there is provided a sprinkling device in which the sprinkling head or member is adapted to be rotated step by step for a portion of a circle in one direction, the direction of rotation being then automatically reversed and the sprinkler head rotates step by step the same distance in the opposite direction.

Such a sprinkler is particularly adapted to the watering along edges of the areas to be sprinkled, and in corners, where a throw of the water in a complete circle is not desired. This present application is a continuation in part of application Ser. No. 261,485, filed March 13, 1939.

There have been a number of prior devices developed in which the part circle principle and the step by step movement of the sprinkler head have been provided. However, in most of these there have been certain definite objections in that but a single control member has been provided to control the movement of the impulse arm in both directions. This has resulted in the movement of the sprinkler head being impositive and difficult to regulate and control.

It is therefore the primary object of the present invention to provide a sprinkler head of the type described, in which the impulse arm has an independent control for its movement in each direction, and which control means is positively set so that the impulse arm and the impulse vane carried thereby will be positively and independently centered in neutral position after each swing of the arm in either direction from such neutral position.

A further object of the invention is to provide positive stop means for the impulse arm control means so that normally there is no possibility of the impulse arm being swung and held to one side of the neutral position, which would prevent the normal operation of the sprinkler.

A further object of the invention is to provide a new and improved and simplified trip means for the sprinkler head rotating arm.

A further object of the invention is to so arrange the sprinkler assembly that there is no necessity of a fine adjustment of the spring control means for the impulse arm in order to positively return and maintain such impulse arm in proper operative position.

A still further object of the invention is to provide a simple means whereby the device may be instantly converted from a part circle to a full circle sprinkler at the will of the operator.

Another important object is to produce a sprinkler which may have a full circle movement in one direction and which may be instantly changed to have a full circle movement in the opposite direction, either movement to be step by step and either movement to be fast or slow at the will of the operator.

I also aim to provide a sprinkler having dual nozzles pointing in the same direction, one for operating the sprinkler and the other for long distance coverage; the two of them providing better coverage than can be had from a one nozzle sprinkler.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a side elevation of the sprinkler, showing the parts in the proper position to enable the sprinkler head to be driven step by step in a counter-clockwise direction.

Figure 2 is a fragmentary sectional elevation of the head or body, showing the water discharging jets.

Figure 3 is a top plan of the sprinkler with the swinging impulse arm removed.

Figure 4 is a fragmentary cross-section on line 4—4 of Fig. 1.

Figures 5 to 8 are diagrammatic plans illustrating the different positions assumed by the impulse arm and associated parts as the arm travels out from its neutral position in the path of travel of the driving stream of water, and then back through the stream to the opposite side thereof to impart a rotative step thereto in the manner to be described.

Description

Referring now more particularly to the characters of reference on the drawings, the sprinkler comprises a hollow body or head 1 having a depending passage spindle 2 turnably mounted in a rigid base 3 adapted for connection to a water supply stand pipe P.

The main nozzle 4 projects radially from the body at an upward angle, and has a water jet 5 at its outer end. An auxiliary nozzle 6, also provided with a water jet 7, projects radially from the body above and in parallel and overhanging

relation to the nozzle 4. This nozzle 6 is preferably shorter than the nozzle 4. Both nozzles are freely open to the interior of the body 1 as shown in Fig. 2.

Above the nozzle 6 is an impulse arm 8, pivoted intermediate its ends on a pin 9 secured in and upstanding from the body approximately at right angles to the axis of nozzle 6. At one end the arm extends beyond the jet 7 and is formed at said end with a fork 10 disposed with its sides laterally spaced. At its opposite end, the arm 8 is formed with a weight 11. A pin 12, disposed at right angles to the axis of the jet 7, is mounted in and depends from the arm 8 just back of the fork 10 and is disposed at right angles to the longitudinal axis of the jet 7. Freely turnable on said pin for limited oscillating movement is a water deflecting vane 13. This vane 13 is normally disposed on a level with and in the path of any stream of water issuing from the jet 7.

The vane is shaped in plan so that its sides are symmetrical to its longitudinal axis. Back of the pin 12 these sides are convexly curved, and converge to a sharp edge E just in front of the jet 7, while on the opposite side of the pin said sides are concavely curved and flare out to form water engaging shoulders 14.

A stop lug 15 projects upwardly from the vane and rides between the sides of the fork 10 to limit the oscillating movement of the vane 13. The extent of movement thus permitted is such that when the arm 8 is longitudinally aligned with the axis of the jet 7, and the lug 15 is engaged with one side or the other of the fork, the sharp edge E of the vane is then disposed to one side or the other of the axis of the jet, depending on which side of the fork is then engaged by the lug 15. Water can thus impinge directly against one side or the other of the vane between the pin 12 and the jet, as clearly shown in Fig. 5.

Fixed in and projecting from the body 1 on opposite sides thereof are aligned horizontal pins 16, on which discs 17 are turnably mounted. The pins 16 are below the pin 9 and their axis substantially intersects that of pin 9, being also at right angles to the axis of the auxiliary nozzle 6. A helical spring 18 is connected at one end to each disc, and at the other end to a collar 19 adjustably mounted on the corresponding fixed pin 16, so that the tension of the spring may be altered by adjustment of the collar. Each spring is enclosed in a housing 17a preferably screw mounted on its disc. Each spring tends to rotate its respective disc so that its upper edge turns toward the nozzle. This movement is limited by the engagement of a radial stop lug 20 on each disc with a corresponding fixed stop 21 on the body 1. Each stop lug 20 also projects into the path of one of two cam fingers 22 fixed on the arm 8 radially of pivot pin 9. These fingers 22 are disposed so that when the lugs 20 are both engaged with their corresponding stops 21, the arm 8 is held against appreciable swinging movement, and is disposed in substantial alignment with jet 7, as shown in Fig. 5.

In order to prevent one or the other of the discs from rotating in a direction to wind up its spring, but to utilize pressure exerted against the disc tending to thus rotate the same, to rotate the sprinkler as a whole, I provide the following structure:

A horizontal bracket 23 projects from the body 1 adjacent the bottom in a direction diametrically opposed to the nozzles. This bracket supports

an upstanding pin 24 on which the sprinkler rotating arm 25 is turnably mounted. This arm projects toward the nozzles to a termination above the body between the discs 17, being formed adjacent said termination with opposed lateral shoulders 26. These shoulders are disposed just back of the lugs 20 when the latter are in their held neutral position and are adapted to be alternately projected into the path of rotation of one or the other of the lugs when the arm 25 is swung to one side or the other, as shown in Fig. 3, where it is interposed in the path of the lower lug 20 shown in that figure.

Turnable on the pin 24 below and independent of the arm 25 is another relatively short arm 27, projecting toward the body 1 and carrying a depending reverse-control stem 28 on its outer end. This stem projects through a movement limiting slot 29 in the bracket 23 and between a pair of circumferentially and independently adjustable movement limiting stop fingers 30 mounted on and projecting from the base 3 substantially radial thereof. A snap action spring unit 31 connects the arms 27 and 25, and acts to cause the arm 25 to suddenly reverse its position when the stem 28, with the rotation of the sprinkler head through an arc for which the fingers 30 are set, engages and is shifted by one or the other of said fingers.

Operation

In operation, the sprinkler head is of course mounted on the water standpipe P as shown in Fig. 1, and the spindle 2 of the head 1 is freely turnable in the base 3, as usual. If such turning movement was unobstructed, the head 1 would then be free to make a complete revolution about the axis of the base 3. However, in the present instance, the sprinkler head is not designed to make such complete revolution. It is constructed and arranged to first make a step by step movement for a portion of a complete revolution, and to then reverse and make a step by step movement in the reverse direction for the same distance as the first movement. This step by step movement first in one direction and then the other is continued until the desired period of irrigation has elapsed.

As will be noted from the foregoing description of the parts, when the sprinkler is in neutral or non-operating position, the impulse arm 8 is held by the springs 18 so that it extends substantially parallel to and above the nozzle jets 5 and 7, and if the stop lug 15 is centered between the sides of the fork 10, the inner sharp edge E of the vane 13 is positioned immediately across the center line of the discharge jet 7. If the parts could remain in these positions and water was discharged from the jet 7, probably no movement of the sprinkler head would take place.

Assuming, then, that it is desired to operate the sprinkler and to start its step by step movement in a counter-clockwise direction, the deflecting vane 13 is moved on its pivot 12 until the curved side A thereof is opposed to any stream of water to be projected from the jet 7, as shown in Fig. 5. The reverse control stem 28 is then moved to a point which would cause the snap action spring 21 to throw the left hand stop shoulder 26 into the path of movement of the stop lug 20, as shown in Fig. 3. Then, when the water is turned into the sprinkler head and the stream or jet is discharged from the nozzle

7, it strikes against the surface A and swings the arm 8 clockwise.

Immediately after the initiation of this clockwise movement, such movement brings the shoulder 14 which extends from the side A into the path of the water jet issuing from the nozzle 7 as shown in Fig. 6, and the impulse imparted thereto by such water jet turns the vane 13 on its pivot 12 so that it assumes a position reverse to that which it had when the movement of the impulse arm was initiated. This reverse position of this vane 13 can be seen in Fig. 7.

The initial impact of the water jet against the side A throws the arm 8 in the outward clockwise movement with considerable force, and this swing continues until the right-hand cam finger 22 engages the right hand stop lug 20 on the right hand disc 17, and causes that disc to rotate against the tension of its corresponding spring 18.

When this resistance of the spring 18 has been built up to a sufficient degree to overcome the force of the swing of the arm 8, the spring then reacts to cause the stop lug 20 to act against the cam finger 22 and return the arm 8 to a positive neutral position. Since the bottom part of the lug 20 comes to rest against the stop lug 15 on the body 1, the action of the spring can do no more than to return such arm 8 to its neutral position.

As the arm 8 returns to neutral position, it is of course carrying with it the vane 13, which has been turned to the position shown in Fig. 7, in the manner described. Thus, as the arm 8 reaches neutral position, the face C of the vane 13 is presented to the impact of the water discharging from the jet 7. This impact then immediately imparts to the arm 8 a reverse or counter-clockwise swing, and as this swing is initiated, the force of the water strikes the right hand shoulder 14 of the vane 13, and again reverses the position of that vane so that it returns to that position shown in Fig. 5, where it is in position to permit the arm 8 to be again thrown with a clockwise movement when the vane again enters the stream as the arm 8 is returned to neutral position after its counter-clockwise swing.

As the arm 8 is given this counter-clockwise movement, the left-hand cam finger 22 strikes the left-hand stop member 20, which in turn strikes the shoulder 26, which at this time blocks the path of the movement of the stop member 20.

Since the shoulder 26 is on the head rotating arm 25, which is in turn associated with the head 1, this impact imparts partial rotative movement to the head itself carrying the nozzles 4 and 6 in a counter-clockwise movement for a short distance. The left-hand spring 18 then reacts to move the left-hand stop member 20 against the left-hand cam finger 22 and again return the impulse arm 8 to neutral position, at which time the surface A is again presented to the water jet and the above described cycle of movement commences over again.

Under the cycle of movement described above, the sprinkler head is moved step by step in a counter-clockwise direction for such arc of movement as is desired. This arc of movement is predetermined by the setting of the stop fingers 30. If a 90° arc of movement is desired, they are set 90° apart. If a 180° arc of movement is desired, they are set 180° apart.

When the sprinkler has moved counter-clockwise through such predetermined arc, the reverse control stem 28 engages the sprinkler right hand finger 30 and the continued movement of the

head causes the stem 28 to be moved across from one side of the bracket 23 to the other. This causes the snap action spring unit 31 to function to throw the head rotating arm 25 to the other side of the head 1 and bring the right-hand shoulder 26 into the path of the right-hand stop 20. When this is done, the entire cycle of movement is reversed, so that the arm 8 will then swing freely to the left side as it had previously swung freely to the right side. Then as it passes through the stream and swings to the right side, the blocked movement of the right-hand stop 20 engaging the right-hand shoulder 26 will impart rotary movement to the sprinkler head in a clockwise direction and in step by step relation, just as it had previously imparted a like movement in a counter-clockwise direction.

From the foregoing description, it will be seen that the swing of the arm in either direction and the movement imparting action thereof to the head 1 is independently controlled on each side by the respective spring 18; that is, each spring of these springs 18 acts independently on one side only of the impulse arm to positively return it to neutral position, and the control of its movement on either side of the head is thus independently regulated. This very definitely distinguishes from that type of sprinkler in which it is intended to control both movements of the impulse arm with a single spring.

By reason of the independent control for each swing of the impulse arm, and the fact that the control means comes each time to a positive position, which brings the impulse arm to neutral, there is no necessity of an exceptionally fine adjustment of the spring being had. Furthermore, there is no possibility of the arm being carried and held past neutral position, which would cause the sprinkler to come to a stop since, once the arm stops past neutral position, the driving vane 13 is held clear of the stream of water discharging from the jet 7 which furnishes the motive power for the sprinkler.

It will also be noted that due to the shifting vane 13, each step of the drive of the sprinkler is induced directly by the force of the water striking the vane 13 and imparting movement to the impulse arm, as contradistinguished from the so-called reaction sprinklers and those in which the movement of the impulse arm is derived in one direction solely by reason of the impulse arm striking an element on the sprinkler head as it returns toward neutral position under the reaction of a spring disposed substantially axially of the impulse arm and directly connected therewith. In my invention it will be noted that there is no direct spring connection between the impulse arm and the spring in that the independent springs on each side thereof do not act directly against the impulse arm, but there are intermediate connections including the stop elements 15 on the body of the sprinkler, which always control the return movement of the stop members 20 so that when once the impulse arm reaches neutral position, no further movement thereof can be imparted thereto by the spring.

By reason of this special and independent spring control means, there are no parts of the sprinkler which can get out of adjustment, but the action thereof in either or both directions is absolutely positive, and is accomplished with a minimum of vibration or risk of dislocation of operating parts.

It is to be particularly noted that another ad-

vantage of my independent and positive control is that even should the sprinkler stand become slightly tilted from the vertical, as often happens in practice, the continued positive action of the parts as described will not be seriously impaired; which advantage is lacking in other types of part-circle sprinklers.

The reverse control stem 28 may be made in two parts hinged at 28a at a point above the stop fingers 30. Thus, when it is desired to convert the device into a full-circle instead of part-circle sprinkler, it is only necessary to move the lower end of this stem 28 on its hinge point so as to clear the stop fingers 30 as shown by dotted lines in Fig. 1, leaving the head 1 then free to move continuously step by step completely about the axis of the stand pipe. This full-circle movement may be either clockwise or counter-clockwise, depending on the position at which the stop shoulders 26 may be set. This means of converting the device at will either into a part-circle or full-circle sprinkler is of a very considerable practical value, as will be obvious.

Furthermore, the tension of each of springs 18 may be adjusted to regulate the speed of return of the impulse arm 8 from a swing in either direction. Thus, any movement of the sprinkler head in either direction may be fast or slow at the selection of the operator.

The dual nozzles 4 and 6 both pointing in the same direction present a feature of great importance. The nozzle operates the sprinkler and the water jetting therefrom is diffused by the operating mechanism into an area close around the standpipe. The other nozzle 4, with its jet being uninterrupted, throws a stream for long distance coverage away from the standpipe; the two nozzles thus making for better distribution than can be had from a one nozzle sprinkler heretofore thought necessary in connection with part circle sprinklers.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A rotary sprinkler comprising a sprinkler head mounted for rotation and having a nozzle projecting therefrom and provided with a jet opening, an impulse arm mounted for oscillatory movement on the head and having a predetermined neutral position, a cam finger on the arm, a disc mounted to turn on an axis on the head, a spring tending to turn the disc, means on the disc engageable with the cam finger, means whereby water issuing from the jet opening will swing the impulse arm outward with the cam finger moving the disc against the resistance of the spring, the disc and spring functioning to act against the cam finger and return the arm to neutral position after each outward swing.

2. A rotary sprinkler comprising a sprinkler head mounted for rotation and having a nozzle projecting therefrom and provided with a jet opening, an impulse arm mounted for oscillatory movement on the head and having a predetermined neutral position, a cam finger on the arm,

a disc mounted to turn on an axis on the head, a spring tending to turn the disc, means on the disc engageable with the cam finger, means whereby water issuing from the jet opening will swing the impulse arm outward with the cam finger moving the disc against the resistance of the spring, the disc and spring functioning to act against the cam finger and return the arm to neutral position after each outward swing;

5 5 swing the impulse arm outward with the cam finger moving the disc against the resistance of the spring, the disc and spring functioning to act against the cam finger and return the arm to neutral position after each outward swing; a 10 stop means on the head and means on the disc engageable with said stop whereby to stop the rotation of the disc after the arm has reached neutral position.

3. A rotary sprinkler comprising a sprinkler head mounted for rotation in a substantially horizontal plane and having a laterally projecting nozzle, an impulse arm mounted on the head for rotation about a fixed axis, means on the arm capable of moving into the jet from the nozzle in such a manner that the force of the jet will alternately swing the arm first to one side of the jet and then to the other, means whereby each alternate movement of the arm in one direction will impart a step by step movement of the head in one direction, the arm when in neutral position being in substantial parallelism with the axis of the nozzle, and opposed springs separately acting on the arm to return the same to neutral position after any swinging movement and tending to hold the arm in such neutral position.

4. A rotary sprinkler comprising a sprinkler head mounted for rotation in a substantially horizontal plane and having a laterally projecting nozzle, an impulse arm mounted on the head for rotation about a fixed axis, means on the arm capable of moving into the jet from the nozzle in such a manner that the force of the jet will alternately swing the arm first to one side of the jet and then to the other, separate springs mounted on the head on opposite sides of said axis, means between the arm and springs to cause the tension of the springs to be alternately and temporarily increased upon alternate swinging movements of the arm and stop means between the head and one spring engageable upon a predetermined tensioning of said spring.

5. A sprinkler as in claim 4, with means to manually control the tension of said one spring.

6. A sprinkler as in claim 4, with means to independently and manually control the tension of the springs.

7. A sprinkler as in claim 4, with means allowing of unwinding of the springs to an extent only sufficient to return the arm to neutral position; the arm when in such position lying in substantial parallelism with the axis of the nozzle.

8. A sprinkler as in claim 4, with means to independently and manually control the tension of the springs, and stop means allowing of unwinding of the springs to an extent only sufficient to return the arm to neutral position irrespective of the initial tension of the springs; the arm when in such position lying in substantial parallelism with the axis of the nozzle.

65 9. A rotary sprinkler comprising a sprinkler head mounted for rotation in a substantially horizontal plane and having a laterally projecting nozzle, an impulse arm mounted on the head for rotation about a fixed axis, means on the arm capable of moving into the jet from the nozzle in such a manner that the force of the jet will alternately swing the arm first to one side of the jet and then to the other, separate springs mounted on the head on opposite sides of said axis, means between the arm and springs to

cause the tension of the springs to be alternately and temporarily increased upon alternate swinging movements of the arm and stop means between the head and the springs alternately engageable upon a predetermined tensioning of the corresponding spring by swinging of the arm in a corresponding direction.

10. A sprinkler as in claim 9, with means to selectively and independently control the initial tension of the springs.

11. A rotary sprinkler comprising a sprinkler head mounted for rotation in a substantially horizontal plane and having a laterally projecting nozzle, an impulse arm mounted on the head for rotation about a fixed axis, means on the arm capable of moving into the jet from the nozzle in such a manner that the force of the jet will alternately swing the arm first to one side of the jet and then to the other, separate helical springs mounted on the head on opposite sides of said axis and disposed in axial alignment transversely of the head at right angles to the arm axis, radially projecting lugs attached to one end of the springs and movable circumferentially about the spring axis to increase the tension of the springs upon movement of the lugs in one direction, stop means limiting unwinding of the springs and corresponding movement of the lugs, cooperating stop means between the head and one spring engageable upon a predetermined movement of the corresponding lug in a spring tensioning direction and opposed fingers on the arm both engaging the lugs when the same is in neutral position and the springs are unwound to their limit.

12. A sprinkler as in claim 11 with means independently and selectively to adjust the initial tension of the springs without affecting the position of the lugs when the springs are unwound to said limit.

13. A rotary sprinkler comprising a sprinkler head mounted for rotation in a substantially horizontal plane and having a laterally project-

ing nozzle, an impulse arm mounted on the head for rotation about a fixed axis, means on the arm capable of moving into the jet from the nozzle in such a manner that the force of the jet will

- 5 alternately swing the arm first to one side of the jet and then to the other, means whereby each alternate movement of the arm in one direction will impart a step by step movement of the head in one direction, the arm when in neutral position being in substantial parallelism with the axis of the nozzle, a spring to return the arm to said neutral position after the arm has swung in one direction, another spring adapted to be tensioned upon swinging movement of the arm in 15 the other direction and functioning to subsequently return the arm to a neutral position and stop means between the head and said other spring engageable in a manner to cause rotation of the head upon a predetermined tensioning of said last named spring.

14. A sprinkler as in claim 13, with means to selectively and independently adjust the initial tension of the springs.

15. In a rotary sprinkler, a sprinkler head 25 mounted for rotation in a substantially horizontal plane, means to cause a rotation of the head in one direction and means operating after the head has moved through a predetermined arc in said one direction to effect a rotation of the head in the reverse direction; such last named 30 means comprising stops on the head on opposite sides of its axis, an arm engageable at one end with the stops alternately, means pivoting the arm at its other end on the head, a relatively 35 short arm pivoted in common with and below the first named arm for rotation independently thereof and extending in the direction of the one end of said first named arm, a stem depending from the outer end of the last named arm, circumferentially spaced stops on the sprinkler 40 below the head and between which the stem projects and a snap action spring unit between the arms.

WILLIAM A. BUCKNER.
